UNITED STATES PATENT OFFICE.

PETER HUSTON, OF CHICAGO, ILLINOIS, ASSIGNOR TO THE ADAMS & WESTLAKE COMPANY, OF CHICAGO, ILLINOIS, A CORPORATION OF ILLINOIS.

SHADE-HOLDER.

1,027,848.

Specification of Letters Patent.

Patented May 28, 1912.

Application filed March 25, 1912. Serial No. 686,023.

To all whom it may concern:

Be it known that I, PETER HUSTON, a citizen of the United States, and resident of Chicago, county of Cook, and State of Illinois, have invented certain new and useful Improvements in Shade-Holders, of which the following is a specification, and which are illustrated in the accompanying drawings, forming a part thereof.

10 The invention relates to that type of shade holders more particularly adapted for use in connection with incandescent electric lamps in which the neck of the shade is clamped by an annular helical spring housed 15 within a casing comprising a fixed member and a flanged nut running upon the fixed member, one of the parts of the housing having an inclined face for contracting the spring upon the shade.

20 The object of the invention is to adapt a holder of this character to yieldingly grip the shade, when the nut is retracted to the full limit of its movement, holding it with sufficient firmness to prevent it from falling 25 by its own weight yet permitting its withdrawal upon the application of force. This object is attained by the construction hereinafter described and illustrated in the accompanying drawings, in which—

30 Figure 1 is a sectional view of the holder on the plane of its axis, the shade being shown in detail and as being securely clamped within the holder. Fig. 2 is a similar view with the nut of the holder retracted 35 to the limit of its movement. Fig. 3 is a sectional detail in perspective of the fixed element of the holder on the same plane. Fig. 4 is a similar view of the nut. Fig. 5 is a detail of the locking ring for preventing 40 the separation of the nut from the fixed element of the holder, and Fig. 6 is a sectional view on the line 6—6 of Fig. 1.

The fixed element 10 of the holder is shown 45 as having the form of a cap centrally apertured for attachment to a supporting bracket, not shown. The form of this element is not essential except that it is provided with an annulus 11 rabbeted, as shown at 12 to provide a seat for the end of the neck of the shade 13 and having an outstanding flattened face 14 below the rabbet. Externally the ring 11 is rabbeted at its upper edge, as shown at 15 and is threaded below the rabbet.

50 The nut 16 is threaded to engage the thread of the ring 11 and is flanged inwardly

5 at its lower end, as shown at 17, this flange having an inclined inner face 18. The inner end of the nut is prolonged beyond the threaded portion and is recessed in its inner face to receive the open locking ring 19 60 which may be sprung into the recess and which is formed of wire of such size that it will project when seated within the recess beyond the threaded face of the nut thereby engaging the shoulder of the rabbet 15 when 65 the nut is turned back or retracted. The locking spring is readily inserted when the nut is turned up to the limit of its movement.

An annular helical spring 20 is seated between the shoulder 14 and inclined face 18 70 and is normally of such diameter that when the nut is retracted it rests upon the upper edge of the inclined face. When in this position the internal diameter of the annular spring is normally less than the external diameter of the shade flange 21, thus preventing the insertion or removal of the shade without the application of sufficient force to compress the convolutions of the spring. 80

85 As shade holders of this type have heretofore been made the inclined face has been located upon the fixed element, the flange of the nut being a flat shoulder. By reversing the position of these faces, as shown and described, the weight of the shade tends to contract the annular spring by forcing it down upon the inclined seat while in the form of the construction heretofore followed, the weight of the shade tended to move the 90 spring to the outer edge of the incline and thereby expand it, permitting the shade to drop of its own weight. It was therefore necessary for the operator to use both hands in the operation of either inserting or removing the shade and much trouble arose from the breakage of shades due to careless handling.

95 By the construction here shown and described, the shade may be inserted or removed without using two hands in the operation and in consequence the danger of dropping the shade by careless handling is eliminated.

100 I claim as my invention—

1. In a shade holder, in combination, an externally threaded ring having a flat face, a nut engaging the ring and having an in-standing flange, the inner face of the flange being inclined, and a helical annular spring 110

seated between the face of the ring and the flange of the nut.

2. In a shade holder, in combination, an externally threaded ring having a flat face, 5 a nut engaging the ring and having an inwardly flange, the inner face of the flange being inclined, a helical annular spring

seated between the face of the ring and the flange of the nut and means for limiting the retractive movement of the nut.

PETER HUSTON.
